BOWED EXPANDER ROLL

Frederick T. Walsh, Boston, Mass., assignor to
 Thomas Leyland Machinery Co., Readville,
 Boston, Mass., a corporation of Massachusetts

Application March 24, 1933, Serial No. 662,451

3 Claims. (Cl. 26—63)

This invention relates to the curved or bowed spreader or expander rolls that are employed in cloth spreading or expanding devices of the type shown and described in U. S. Letters Patent No. 1,697,830, granted January 1, 1929. These curved spreader or expander rolls are composed of a curved non-rotating supporting rod or bar disposed transversely of the travel of the cloth, and a series of bobbins or clutches mounted end to end closely adjacent each other on the stationary bar with capacity to revolve on the latter. In certain instances a tubular rubber covering, continuous from end to end of the series of bobbins is necessary or desirable, for the purpose of increasing the frictional engagement between the curved roll thus formed and the cloth, or on account of the delicate nature of the cloth, or for other reasons.

These rubber coverings have been relatively short-lived, because they eventually work loose on their supporting bobbins and operate in faulty manner requiring replacement. Unless they fit tightly on their bobbins or clutches, the rubber coverings tend to shift endwise out of proper working position, resulting in damage to themselves or to the cloth or both, to bulge and get out of round, and eventually to twist and break. Attempts to fix the coverings to the bobbins by locking them to the inside surface of the cover through interengaging projections and depressions on these opposed surfaces have left room for improvement, because of the inherent tendency of the roll to swell and increase both its exterior and interior diameters as a result of the rolling action incident to its use. As soon as this swelling loosens the covering sufficiently to permit relative motion between its interior surface and the opposing bobbin, the resultant wear of the interior surface not only increases the bore, aggravating the trouble, but the worn-off rubber particles soon collect in bunches between the surfaces of adjacent bobbins and the covering, forming humps at the exterior working surface of the covering which both interfere with the proper working of the expander and put destructive strains on the covering itself.

To overcome these drawbacks and extend the useful life of these relatively expensive coverings, and to afford improved frictional engagement between the roll surface and the cloth, and to attain other advantages, the invention comprises the combination with a stationary curved bar and bobbins rotatable thereon, of a rubber covering in or on which are arranged expansion-resisting cords. These cords, preferably helically

disposed, prevent the expansion of the interior and exterior diameters of the rubber sleeve, ensuring a tight fit between the bobbins and the covering preventing relative motion either endwise or circumferential, and because they have little or no appreciable width nor overlap they do not detract from the transverse resilience or interfere with the endwise contraction and extension essential to the roll's rotation about a curved axis. Additionally, through being embedded in or applied to the working surface of the rolls so that portions of the cords are exposed, they can be used to form a surface having desirable frictional and cloth-directing qualities.

Illustrative embodiments of the invention in its preferred form are shown in the accompanying drawing in which,—

Fig. 1 is a portion of a bowed expanded roll having the improved covering of the invention, partly in section.

Fig. 2 is a transverse section of a bowed expander roll, showing one way of employing the cords in the covering.

Fig. 3 is a section similar to Fig. 2 showing a two-ply rubber covering applied, with the cords differently arranged.

Fig. 4 is a partial transverse section of a portion of the covering alone, showing another embodiment.

Fig. 5 is a longitudinal section of a portion of the covering alone, showing still another application of the invention principles.

The bowed shaft 1 carries the usual bobbins 3 arranged end to end in close proximity, and turning freely on the shaft 1. The bobbins are provided at their ends with the usual bushings 5 providing bearing surfaces on the shaft, and with adjacent lubricant-holding felt washers 7. The flexible rubber covering 8 is mounted on the exterior of the bobbins. The bobbins may be of any desired or suitable exterior shape, and preferably will be polygonal in section as shown in Figs. 2 and 3 for the better prevention of relative rotation between the bobbins and the covering. Also, some or all of the bobbins may have a slightly raised circumferential rib 9 helping to prevent endwise movement of the covering, as disclosed in U. S. Patent No. 1,719,375, July 2, 1929.

Embedded in or otherwise incorporated with the rubber of the covering 8 are the cords 10, preferably of fibrous material, though they may be of other material and even of metal so long as they satisfy the invention requirements. These cords, being employed primarily to prevent increase in the diameter of the covering, must offer

no substantial resistance to transverse bending of the roll, and hence as applied they must have little or no direction of extent lengthwise of the covering. They may be disposed in the form of 5 layers of helical windings of continuous cords or groups of cords each extending helically from one end of the covering to the other, the successive turns of each helix being either contiguous or, preferably, slightly spaced, as desired, and the 10 several layers being spaced from each other also if desired by intervening thicknesses of rubber, as shown in Fig. 1 where three spaced plies of helical windings are used.

Alternatively, the cords may be disposed in parallel 15 relation in a sheet or warp, and embedded in or impregnated with rubber and the whole sheet wrapped one or more times about the series of bobbins when disposed in proper relation on a straight shaft, or about a form taking the place 20 of these bobbins, and vulcanized; this form is shown in Fig. 2. Or the warp and a sheet of rubber may be wound successively or simultaneously 25 about the series of bobbins or the form, pressed and rolled into intimate association and into cylindrical shape, and then vulcanized. In this arrangement, each cord may lie in a radial plane as a flat spiral, or may follow a helical course, if desired.

Fig. 3 shows the arrangement of cords in a soft-surfaced rubber roll covering, a ply of cords 14 being incorporated in the tough rubber 16 which engages the bobbins 3 and gives the covering its strength; additional plies of cords 18 may be employed in the soft rubber surfacing 20 if desired. 30 Here the soft rubber surfacing material in sheet form and with the cords embedded therein in the form of a warp is applied in two layers, each of which encircles the tough rubber core without overlapping itself, so that each cord encircles the roll just once, the successive layers being applied 35 so as to break joints. Or the cords and sheet rubber may be applied successively and independently. In Fig. 4 the cords 18 are employed only in the tough rubber core 16.

In the form of Fig. 5, the cords 22 forming the 45 outermost ply are arranged so as to be partially exposed at the exterior surface of the covering 8 to form substantially peripheral ribs thereon, modifying the frictional effect of this surface on the fabric and also giving a corrugated or wavy 50 surface to the roll possessing known advantages in preventing excessive expanding or tearing of

the cloth and otherwise securing improved results. For this purpose, the cords of the surface may be of increased cross-section, well above the embedded cords 10, if desired.

Because no allowance has to be made, in fitting the sleeve to the bobbins, for the usual subsequent 5 diametrical expansion as a result of use, the interior bore of the sleeve can approximate very closely the size of the bobbin, instead of having to be materially less as usual. As a result, the covering 10 does not contract into the interstices between the meeting ends of the bobbins or clutches when at the convex side of the bend of the roll, to be pinched and bitten off at these points by the convergence of the bobbins when arriving at the concave side of the bend. Thus this cause of injury 15 to the covering, and its resultant drawback of releasing fragments of rubber to gather in bunches forming humps in the contour of the roll exterior, is largely or completely avoided. 20

While I have illustrated and described certain forms in which the invention may be embodied, I am aware than many modifications may be made therein by any person skilled in the art, without departing from the scope of the invention 25 as expressed in the claims. Therefore, I do not wish to be limited to the particular forms shown, or to the details of construction thereof, but

What I do claim is:—

1. A roll covering for a bowed expander roll 30 comprising in combination a sleeve of resilient material and cords embedded in the material encircling the roll covering in radial planes.
2. A roll covering for a bowed expander roll comprising in combination a rubber sleeve and 35 cords embedded in its working surface providing substantially peripheral ribs thereon.
3. In a cloth expander, in combination, a bowed shaft, a plurality of bobbins rotating freely thereon each about a different axis, a rubber covering 40 removably surrounding and supported by the bobbins for rotation about the center of the shaft, and expansion-resisting elements extending about the covering in spaced relation to each other holding the latter in rotation-preventing relation with the bobbins, each circuit of such elements about the covering lying substantially in a plane transverse to the covering so as to permit lengthwise expansion and contraction of the 45 covering.
